UNITED STATES PATENT OFFICE

2,677,136

ELECTRIC BABY ROCKER

George Samko, Hopewell, Va.

Application July 22, 1952, Serial No. 300,140

3 Claims. (Cl. 5—109)

1

This invention relates to baby cribs, and more particularly to a baby crib provided with means for oscillating same.

A main object of the invention is to provide a novel and improved electrically driven oscillating baby crib, said baby crib being simple in construction, involving relatively few parts, and being easy to install.

A further object of the invention is to provide an improved electrically driven oscillating baby crib which involves inexpensive components, which is sturdy in construction, which provides a smooth oscillating action, and which is safe to use.

Further objects and advantages of the invention will become apparent from the following description and claims, and from the accompanying drawings, wherein:

Figure 1 is a side elevational view of an improved baby crib constructed in accordance with the present invention.

Figure 2 is an end elevational view, partly broken away, of the baby crib of Figure 1.

Figure 3 is an enlarged cross sectional detail view taken on line 3—3 of Figure 1.

Figure 4 is an enlarged cross sectional detail view taken on the line 4—4 of Figure 1.

Figure 5 is an enlarged fragmentary cross sectional detail view taken on the line 5—5 of Figure 2.

Figure 6 is an enlarged cross sectional detail view taken on line 6—6 of Figure 5.

Figure 7 is an enlarged cross sectional detail view taken on the line 7—7 of Figure 3.

Figure 8 is an enlarged cross sectional view taken on the line 8—8 of Figure 4.

Referring to the drawings, the baby crib is designated generally at 11 and comprises the transverse end boards 12 and 13, which may be the end boards of a conventional baby crib of the stationary type. The end boards 12 and 13 are connected by the longitudinal rod members 14 to define a rigid rectangular framework, and the end boards may comprise vertical corner posts elements 15, 15 connected at their top and bottom portions by the transverse rod members 16 and at their intermediate portions by the spaced horizontal transverse bars 17, 17 which are grooved to receive the end panels 18.

Designated at 19 is the baby bed which includes the transverse end walls 20 and 21. Secured to the upper portion of the transverse end wall 20 is a bracket member 22 formed with the longitudinally extending shaft element 23 which extends rotatably through a bearing 24 provided

2

in the upper portion of the panel element of the end board 12, as shown in Figure 5, and secured to the upper portion of the end wall 21 of the baby bed is another bracket plate 25 formed integrally with the longitudinally extending shaft element 26, longitudinally aligned with the shaft element 23, which extends rotatably through a bearing 27 secured in the upper portion of the panel 18 of end board 13. The baby bed 19 is thus supported for oscillation around a longitudinal axis located at its upper portion.

Vertically secured to and extending through the bars 17, 17 are the spaced rod members 28, 28. Adjustably secured to the rod members 28, 28 as by clamping bars 29 and 30 transversely embracing said rod members is a vertical plate member 31, said plate member being secured to the clamping bars 29 and 30 by respective bolts 32 and wing nuts 33, as shown in Figure 3. The clamping bars 29 and 30 are provided at their ends with the clamping bolts 34 provided with wing nuts 35, whereby the plate member 31 may be adjustably secured at a desired elevation along the rods 28, 28. The plate member 31 is formed with a horizontal stud element 36, and pivotally secured thereto for rotation around a longitudinal horizontal axis is an electric motor 37 mounted substantially vertically, as shown in Figures 1 and 3 and having the depending shaft 38. Secured on the shaft 38 is a relatively small gear 39 which meshes with a larger gear 40 journalled to the bottom of the motor housing and formed in its face portion with an eccentrically located, generally circular groove 41.

Formed integrally with the stud element 36 is the depending arm 42 which is provided at its ends with the vertical roller 43 engaging in the groove 41. Since the arm 42 is stationary, rotation of the motor shaft 38 causes the motor to oscillate around its horizontal pivotal supporting axis, the axis of the gear 40 being located in transverse alignment with the motor shaft 38, whereby the rotation of the motor shaft produces an oscillating reaction causing the motor to swing from side to side. The lower end of the motor shaft 38 extends through an aperture in a longitudinally extending plate member 44 secured to the bottom of the baby bed 19, whereby the oscillation of the motor 37 is transmitted to the baby bed.

It will be readily apparent that when the motor 37 is energized, the baby bed 19 will be caused to oscillate around its axis of rotation.

As shown in Figure 7, the motor 37 is rotatably supported in the stud 36, the motor being pro-

vided with a supporting shaft 45 which is rotatably received in stud 36, said shaft 45 being formed with an annular groove 46 in which is engaged the end of a retaining screw 47 for normally preventing disengagement of the shaft 45 from the supporting stud 36.

While a specific embodiment of an improved oscillating baby crib has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a baby crib, a pair of spaced transverse end boards, means rigidly connecting said end boards, a baby bed, means swingably supporting said bed on said end boards for rotation around a longitudinal axis located adjacent the top ends of the boards, a bracket secured to one of said boards, a vertically positioned electric motor pivoted to said bracket for rotation around an axis parallel to the above-named longitudinal axis, cooperating cam means on said bracket and on the motor shaft arranged to oscillate the motor relative to said bracket responsive to rotation of said shaft, and coupling means rigidly secured to said bed and engaging the motor shaft, said shaft cooperating with said last named means to oscillate the bed.

2. In a baby crib, a pair of spaced transverse end boards, means rigidly connecting said end boards, a baby bed, means swingably supporting said bed on said end boards for rotation around a longitudinal axis located adjacent the top ends of the boards, a bracket secured to one of said boards, a vertically positioned electric motor pivoted to said bracket for rotation around an axis parallel to the above-named longitudinal axis,

10
15

cooperating cam means on said bracket and on the motor shaft arranged to oscillate the motor relative to said bracket responsive to rotation of said shaft, and a horizontal longitudinally extending plate member rigidly secured to said bed and engaging the motor shaft, said plate member being formed with an aperture rotatably receiving the motor shaft and cooperating with said shaft to cause oscillation of the bed.

3. In a baby crib, a pair of spaced transverse end boards, means rigidly connecting said end boards, a baby bed, means at the upper portions of the opposite ends of the bed swingably supporting said bed on said end boards for rotation around a longitudinal axis located adjacent the top ends of the boards, a bracket secured to one of said boards, a vertically positioned electric motor pivoted to said bracket for rotation around an axis parallel to the above-named longitudinal axis, cooperating cam means on said bracket and on the lower portion of the motor shaft arranged to oscillate the motor relative to said bracket around said last-named axis responsive to rotation of said shaft, and a horizontal longitudinally extending plate member rigidly secured to said bed and engaging the motor shaft, said plate member being formed with an aperture rotatably receiving the motor shaft and cooperating with said shaft to cause oscillation of the bed.
